UNITED STATES PATENT OFFICE.

ERNST WISROTH, OF LOS ANGELES, CALIFORNIA, ASSIGNOR OF ONE-HALF TO
REGINALD D. RAPHAEL, OF LOS ANGELES, CALIFORNIA.

ICE-CREAM-VENDING CABINET.

Application filed October 31, 1921. Serial No. 511,702.

To all whom it may concern:

Be it known that I, ERNST WISROTH, a citizen of the United States, residing at Los Angeles, in the county of Los Angeles and

5 State of California, have invented new and useful Improvements in Ice-Cream-Vending Cabinets, of which the following is a specification.

My invention relates to apparatus for 10 vending ice cream in the form of bricks, and it has particular reference to certain new and useful improvements over the apparatus as embodied in my co-pending application Serial No. 465,160, filed April 28, 1921.

15 The purpose of my present invention is the provision of a storage and dispensing receptacle adapted for use in conjunction with and to supplant the present receptacle embodied in the co-pending application above

20 referred to. The construction of the receptacle, in its present embodiment, is such as to prevent the adhesion of the bricks of cream to the walls of the dispensing magazine, and to thereby insure of the successful 25 operation of the apparatus. The receptacle is also provided with storage magazines for the bricks of cream, and doors and door controlled openings through which the bricks can be supplied to and removed from 30 the several magazines.

I will describe one form of vending apparatus embodying my invention and will then point out the novel features thereof in claims.

35 In the accompanying drawings,

Figure 1 shows in side elevation and partly in section, one form of vending apparatus embodying my invention.

Fig. 2 is a fragmentary view showing the 40 receptacle in front elevation.

Fig. 3 is a transverse sectional view of the apparatus shown in Fig. 1.

Similar reference characters refer to similar parts in each of the several views.

45 Referring specifically to the drawings and particularly to Fig. 1, my invention, in its present embodiment, comprises a hollow base designated at B which contains the mechanism (not shown) adapted to effect 50 the operation of the mechanism for causing the dispensing of bricks from a receptacle designated generally at R and superimposed on the base. The receptacle R comprises, in the present instance, a tank preferably of 55 rectangular form, the walls of which are

provided with the necessary heat insulating material designated at 15 in Fig. 1 for maintaining a freezing temperature within the receptacle.

As illustrated to advantage in Fig. 1, 60 the receptacle is constructed to provide an ice compartment 16, the bottom of which is formed to provide a drain which communicates with a pipe 16^a extending to a point exteriorly of the receptacle. At the rear 65 side of the compartment, preferably in the corners thereof, are arranged storage magazines 17 in which the bricks of cream are adapted to be stored. Access is had to the 70 interior of the receptacle for the placing of the bricks and ice therein through an opening formed in the top, such opening being controlled by a door 18 (Fig. 1) hingedly supported thereon.

At the front side of the receptacle a 75 hingedly supported door 19 controls an opening for gaining access to a pair of dispensing magazines designated at M. This door is preferably formed with glass panels 80 20 through which a customer may observe the contents of the magazines. Each of the dispensing magazines is separated from the ice compartment by walls 23 and includes a plurality of vertically extending rods 21 85 arranged in spaced relation and secured at their upper and lower ends to metallic frames 22, the lower frame 22 surrounding an opening in the floor through which the bricks of cream may be dispensed by mechanism of the character illustrated and described in my co-pending application previously referred to, such mechanism including a member 24 supporting the stack of cream bricks within the magazine and 90 adapted to be lowered to bring the lowermost brick into the path of an ejector 25 by which it will subsequently be ejected from the machine. As shown in Fig. 1, the forward side of each magazine is open so 95 as to allow of the insertion of the bricks of cream therein, and to present an unobstructed view of the bricks through the glass panels of the door.

The purpose of constructing the dispensing magazines of rods is to present the smallest possible contacting surface to the bricks of cream within the magazine, and to thereby prevent the adhesion or freezing of the bricks to the walls of the magazine. 100 When constructing the wall of the magazine 110

so as to present a large contacting surface to the bricks of cream, it has been found that the bricks actually freeze to the walls and thus adhere thereto to such an extent 5 as to prevent the discharge of the bricks from the magazines, and thereby preventing the successful operation of the apparatus. By employing the rods 21, this difficulty is overcome so that the proper 10 feeding of the bricks from the magazines is insured.

Although I have herein shown and described only one form of vending apparatus embodying my invention, it is to be 15 understood that various changes and modifications may be made herein without departing from the spirit of the invention and the spirit and scope of the appended claims.

What I claim is:

20 1. In an ice cream vending apparatus, a receptacle constructed to provide an ice compartment, storage magazines arranged

within said compartment, a door controlled opening for gaining access to the compartment and to said magazines, dispensing 25 magazines within the compartment, a door controlled opening for gaining access to the dispensing magazines, said dispensing magazines being formed of rods arranged in spaced relation to each other and having an open side through which the bricks of cream are adapted to be placed into and removed from the magazines.

2. In an ice cream vending apparatus, a receptacle, dispensing magazines within the 35 receptacle, each of said magazines being constructed to present a relatively small contacting surface to bricks of cream contained within the magazines whereby the adherence of the bricks to the walls of the 40 magazine is prevented.

In testimony whereof I have signed my name to this specification.

ERNST WISROTH.
